DESIGN FOR A CANDLE

Paul A. Williams, Ebenezer, N. Y., assignor to
The W. & F. Manufacturing Co., Inc., Buffalo,
N. Y.

Application February 21, 1947, Serial No. 137,078

Term of patent 7 years

(Cl. D73—1)

To all whom it may concern:

Be it known that I, Paul A. Williams, a citizen of the United States, residing at Ebenezer, county of Erie, State of New York, have invented a new, original, and ornamental Design for Candles, of which the following is a specification, reference being had to the accompanying drawing, forming a part thereof.

In the accompanying drawings:

Fig. 1 is a front elevation of a candle showing my new design;

Fig. 2 is a rear elevation of the same;

Fig. 3 is a side elevation of the same; and

Fig. 4 is a plan view of the same.

I claim:

The ornamental design for a candle, substantially as shown.

PAUL A. WILLIAMS.
